US0D1105130S

(12) **United States Design Patent** (10) Patent No.: **US D1,105,130 S**
Yu et al. (45) Date of Patent: ** Dec. 9, 2025

(54) **DISPLAY SCREEN WITH GRAPHICAL USER INTERFACE**

(71) Applicant: **Anker Innovations Technology Co., Ltd.**, Changsha (CN)

(72) Inventors: **Wenjun Yu**, Shenzhen (CN); **Hongzhi Yan**, Shenzhen (CN); **Zhichao Xiong**, Shenzhen (CN)

(73) Assignee: **Anker Innovations Technology Co., Ltd.**, Changsha (CN)

(**) Term: **15 Years**

(21) Appl. No.: **29/968,700**

(22) Filed: **Oct. 17, 2024**

(51) LOC (15) Cl. **14-04**

(52) U.S. Cl.

USPC **D14/485**

(57) **CLAIM**

The ornamental design for a display screen with graphical user interface as shown and described.

DESCRIPTION

The FIGURE is a front view of a display screen with graphical user interface showing our new design.

The peripheral broken line shows a boundary of the claimed design and the display screen and forms no part of the claimed design. The broken lines depicting the alphanumeric characters and the dashes form no part of the claimed design.
